UNITED STATES PATENT OFFICE

PER ALBERT FRESK, OF ROBERTSFORS, SWEDEN

METHOD OF CHARGING CELLULOSE DIGESTERS AND MEANS THEREFOR

Application filed September 25, 1928, Serial No. 308,330, and in Sweden September 1, 1928.

It is previously known to charge cellulose digesters by introducing the charge into the digester under the influence of a flowing medium, preferably an air-stream, whereby the 5 charge will be evenly and tightly packed.

For carrying this method into effect, an injector-like contrivance is used which is so devised that the charge will, at the transition from a pipe or nozzle into a wider pipe 10 opening into the digester, be subjected to the influence of an air-stream brought about by means of a fan, said air-stream being forced in through an annular opening between the two pipes. The larger pipe extends for a certain 15 length into the digester, the air blown in escaping again between the pipe and the wall of the digester. Then the escaping air is again conducted to the fan, through which a vacuum is produced in the digester at 20 the same time.

This known method brings about proper filling, it is true, whereas it will be found impossible in this manner also to fill the uppermost part of the digester with chips. For 25 this reason it has been necessary to interrupt the filling operation as soon as the charging material would reach such a level as to touch the spreading means provided in the apparatus and suspending into the digester. There- 30 fore, it has not been possible to bring about complete filling in the manner described, inasmuch as a more or less smooth cone would always be formed under the mouth of the pipe conducting the chips into the di- 35 gester. Moreover, the ventilator would, toward the end of the filling operation, be subjected to the risk of chips being sucked into the same. Thus there would be produced an empty space in the digester amount- 40 ing about to 8% of the volume of the whole digester, which space cannot be filled with the apparatus. Hitherto, it has been necessary to fill the said empty space manually upon removal of the apparatus from the neck of 45 the digester. One or two men would then descend into the upper part of the digester to spread the charge falling down from the supply conduit for the chips by means of shovels toward the sides of the digester, 50 until the latter would be completely filled.

This subsequent filling by hand requires much time and is also dangerous to the health by reason of the high temperature and on account of the presence of sulphur gases in the digester. Moreover, the subsequent filling 55 by hand is far behind filling brought about by blowing the charge into the digester, as far as tightness is concerned, and the total output will consequently be less.

The object of the present invention is to 60 overcome the said difficulties, and to bring about the same compactness of the filling in the upper part of the digester as in the other parts thereof, by means of one and the same apparatus, and without the same having to 65 be disconnected.

The novel method according to the invention consists in that the circulation of the air coming from the fan and flowing through the filling device, the digester and the fan, is in- 70 terrupted toward the end of the filling opera- 75 tion, so that the air is then blown out into the atmosphere from the digester. It has been found that the chips will by this means be carried out toward the walls of the digester to a greater extent than before, so that the surface of the charge will finally form a conical recess having its apex directed downwards. In this manner the filling is ren- 80 dered very complete, and upon finishing the 85 same there is only left the space occupied by the pipe through which the chips are blown into the digester. This empty space can, if desired, be readily filled subsequently by simply admitting a corresponding quantity of chips. In order to collect the chips forced out of the digester by the stream of air, there is preferably provided a basket of metal cloth over the outlet of the digester, said basket being adapted to catch the chips discharged. 90

The accompanying drawing illustrates an embodiment of the invention by way of example, the filling device being viewed in longitudinal section.

The air-stream required for the charging 95 is conducted from a fan or other suitable air compressor through the conduit 1 into the space 2. This fan may be similar to the fan in my Patent No. 1,876,691. The charge (the chips), which is filled into the hopper 21 100

falls further down into the hopper 32. The compressed air from the space 2 flows down through the intervening space between the hopper 32 and the pipe 7 and then entrains 5 the chips down the pipe and forces the same down into the digester 21. From the digester the air is again sucked up by the fan, which is for this purpose connected to the neck of the digester by means of a conduit 22. Shifting 10 of the air-stream is effected by means of the annular dampers 25 and 26 which are turned by the two handles 23 and 24 to such an extent as to open the dampers outwardly. At the same time the damper 29 is introduced 15 into an opening 27 in the conduit 22 between the two dampers 25 and 26. By this means the sucking of air from the digester is interrupted, and the air is instead forced out through the slots 34 of the annular damper 25, while the fan is now sucking air from the 20 outside through the slots 35 of the damper 26. In order to facilitate collection of any chips that may be forced out with the air-stream through the slots of the damper 25, 25 the latter is surrounded by a catching device such as a round basket 30 of metal cloth.

What I claim is:—

1. Method of charging a cellulose digester by first introducing the charge into the 30 digester under the influence of the circulation of compressed fluid, then conducting the fluid out of the digester, thereupon interrupting the circulation of the fluid towards the end of the filling operation in such a manner that the charge at the top of the digester is stacked in the form of an inverted cone, while the fluid from the digester is blown out 35 into the atmosphere.

2. Apparatus for charging a digester, 40 comprising a hopper communicating with the filling opening of the digester, a drum surrounding the mouth of the hopper, a nozzle on said drum extending into the digester opening, a conduit from a source of compressed fluid adapted to conduct the fluid into said drum, past the hopper mouth through said nozzle into the digester, a second conduit for returning the fluid to said source from said opening, and means in said 45 second conduit for directing the fluid flow into the atmosphere.

3. An apparatus as described in claim 2, 50 said fluid changing means comprising a damper to be inserted transversely in said conduit and sleeves revolvably mounted on each side of said damper and provided with apertures adapted to register with corresponding apertures in the conduit when the sleeves stand in open position and to close 55 said apertures when the sleeves stand in closed position.

4. An apparatus as described in claim 2, 60 said fluid changing means comprising a damper to be inserted transversely in said conduit and sleeves revolvably mounted on

each side of said damper and provided with apertures adapted to register with corresponding apertures in the conduit when the sleeves stand in open position and to close 70 said apertures when the sleeves stand in closed position, and a perforated basket enclosing one of said sleeves.

In testimony whereof I affix my signature.
